UNITED STATES PATENT OFFICE.

CHARLES E. BROOKS, OF ST. LOUIS, MISSOURI, ASSIGNOR TO B. ROTH TOOL COMPANY, OF ST. LOUIS, MISSOURI, A CORPORATION OF MISSOURI.

STRIP-FEEDING MECHANISM.

No. 901,517.

Specification of Letters Patent.

Patented Oct. 20, 1908.

Original application filed March 31, 1908, Serial No. 424,308. Divided and this application filed June 29, 1908.
Serial No. 440,799.

To all whom it may concern:

Be it known that I, CHARLES E. BROOKS, a citizen of the United States, and a resident of the city of St. Louis and State of Missouri, 5 have invented a new and useful Improvement in Strip-Feeding Mechanisms, of which the following is a specification.

The subject matter of the present application is divided out of an application for 10 patent for an improvement in embossing and printing presses, Serial No. 424,308, filed by me March 31, 1908.

The present invention relates to the mechanism for feeding the wiping paper and has 15 for its principal objects to intermittently feed a predetermined length of paper, which length may be varied at pleasure.

Another object is to provide against the creasing of the wiping paper on the wiping 20 pad.

The invention consists principally in a belt operatively connected to the actuating mechanism to be moved intermittently and arranged to frictionally engage the supply roll.

25 It also consists in means for taking up the slack of the waste paper on each side of the wiping pad.

It also consists in the combinations and arrangements of parts hereinafter described 30 and claimed.

Figure 1 is a vertical section through an embossing and printing press embodying my invention, portions being omitted; Fig. 2 is an enlarged isometric view of a portion of the 35 machine showing the paper strip feeding device; Fig. 3 is a fragmentary elevation of a portion of the rack-actuating mechanism for the paper strip feeding device; Fig. 4 is a detail view partly in section showing the winding mechanism and slack taken up for the paper strip; and, Fig. 5 is a detail view of the crank arm.

In the operation of an embossing and printing press of the type fully described in 45 my copending application for Letters Patent No. 424,308, filed March 31, 1908, the die is mounted on a carrier A which is arranged to be reciprocated horizontally by the actuating mechanism. The mechanism for inking the die is located in the rear portion of the machine and is arranged to ink the die in its rearmost position. The plunger or impression mechanism is located at the front of the

machine and is arranged to coöperate with the die in its foremost position. Above the 55 path of the die carrier is the wiping pad B, whose function is to remove all excess ink from the die. This wiping pad is intermittently reciprocated vertically. Its connections to the actuating mechanism are such 60 that it remains in its lowermost position while the die carrier is moved past it in traveling from the inking mechanism to the impression point. The lower portion of the wiping pad is more or less resilient and in 65 practical operation is partially covered by a strip of paper commonly known as the wiping paper or strip. As the die is carried past the wiping pad, the excess ink thereon is wiped off by the paper, whereupon the wiping 70 paper is fed to bring a fresh portion thereof into operative relation to the die. All of these constructions and operations are 75 fully described in my copending application, and I consider it unnecessary to describe them in further detail.

The wiping paper is delivered in a continuous strip 1 from a supply roll 2 conveniently located above the wiping pad. From the supply roll the strip of winding paper passes 80 downwardly around the wiping pad and thence upwardly to a conveniently located winding drum 3. The supply roll has a hollow core through which extends a horizontal rod or bar 4 whose ends are suitably supported in the frame 5 of the machine, whereby the supply roll is journaled or rotatably mounted on said rod. Journaled in the framework parallel with said rod and on opposite sides thereof are two spindles 6, 7. 90 One of these last mentioned spindles is provided with a coiled spring 8, one end of which is fixed to the framework and the other end of which is fixed to said spindle 6, whereby said coiled spring tends to turn said spindle 95 backwardly. Said spindle 6 also has one end of a friction strap or band 9 fastened thereto and wound around it. The other end of this friction strap is fastened to the other parallel spindle 7 around which it is wound. The 100 spindle 7 (hereinafter called the feed spindle) has a pinion 10 fixed thereon which meshes with a rack 11 which is connected to the actuating mechanism of the machine so as to be reciprocated intermittently thereby. In 105 the construction illustrated in the drawing,

the lower end of the rack is connected to a rock arm or lever 12 which is pivoted on the frame of the machine. This lever is connected by a rod 13 to a crank arm 14 fixed on a rock shaft 15 which is operatively connected to the main driving shaft. The crank arm 14 has a longitudinal slot 16 in which fits a member 17 of the locking device which fastens the rod to the crank arm. By shifting 10 this member longitudinally in the slot, the stroke of the rod, and, consequently, the stroke of the feeding rack are varied. In order to keep the rack 11 in operative relation to the pinion or gear wheel 10 of the feed 15 spindle 7, the rack extends through a guide 18 that is journaled on or concentric with said feed spindle. By this arrangement, the coiled spring on the spindle 6 keeps the friction strap wound taut so that said strap is 20 kept in contact with the periphery of the supply roll. At the same time, the coiled spring allows the strap to unwind from the spindle 6 and rewind on the feed spindle 7 when the actuating mechanism moves the 25 rack to turn said feed spindle. On account of the frictional engagement of the strap against the periphery of the supply roll, the forward movement of the strap feeds a definite length of the wiping strip, which length 30 depends upon the stroke of the feed rack. This feed movement of the wiping strip is effected during the movement of the winding drum to take up a length of waste paper equal to the amount fed, as hereinafter described, before the back stroke of the feed 35 rack. In consequence of this relation, the friction strap is wound back onto its spring spindle idly or without effect upon the roll, except, however, that it will rewind the supply roll far enough to take up any slack in the 40 strip on the feed side of the wiping pad.

As stated above, the strip of wiping paper passes under the wiping pad and thence to a winding drum. This winding drum 3 is fully 45 described and illustrated in said application for patent Serial No. 424,308. It comprises a drum or core journaled on the framework of the machine and operatively connected to the actuating mechanism by a friction clutch.

50 As illustrated in the accompanying drawing, the core of the winding drum has a pinion 19 loosely journaled thereon, which pinion meshes with a rack 20 which is connected by a link or rod 21 to an arm 22 on the above mentioned rock shaft 15 that is adapted to be oscillated by the actuating mechanism. Preferably, the rock arm 22 is slotted longitudinally so that the connection of the link thereto may be adjusted at pleasure so as to 55 vary the stroke of the rack. The end of the pinion 19 is flanged or enlarged, and provided with pawls 23 on its face which overlap and co-operate with a ratchet wheel or ring 24 that is loosely journaled in the shaft or core of the 60 winding drum. One face of this ratchet ring 65 bears against the face of a second ring or wheel 25 which has ratchet teeth in its periphery and is fixed to the core of the shaft. Pawls 26 are mounted on a fixed member of the frame in position to co-operate with the ratchet teeth of said last mentioned ring. The two ratchet rings abut against each other, and constitute the members of a friction clutch. The loose member 24 of the clutch is pressed against the fixed member 70 75 25 by a suitable spring whose pressure is varied by any suitable adjusting device, such as that illustrated in said application No. 424,308.

By the arrangement just described, the rock shaft 15 is intermittently oscillated by the actuating mechanism. The motion of the rock shaft causes a reciprocatory motion of the rack 20 which in turn transmits rotary motion to the pinion 19. The motion of the pinion is transmitted through its pawls to the friction clutch to effect the rotation of the winding drum. When the rotation of the winding drum has proceeded far enough to take up the slack of the waste paper, the friction clutch yields, permitting the continued movement of its loose member while the fixed member remains stationary. In this position, the pawls of the frame lock the fixed member of the clutch against backward 90 rotation, so that the return stroke of the rack restores the loose member of the clutch idly to its initial position. In order to vary the feed, it is only necessary to shift the connecting device in the longitudinal slot of the rock 95 arm 22. The parts are so correlated to the actuating mechanism that the feed movement of the supply roll begins later and stops earlier than the movement of the waste paper winding mechanism, this winding movement 100 ceasing before the wiping pad reaches its lowermost position. The wiping pad thus tends to take up any slack and the wiping strip is thus kept smooth and unwrinkled below the wiping pad.

110 While the present invention is particularly applicable in connection with the movements of the wiping strip of an embossing and printing press, it is obviously capable of general use and I do not wish to restrict myself to the specific construction herein described.

115 What I claim as my invention and desire to secure by Letters Patent is:

1. A strip feeding device comprising a spindle and means for intermittently rotating the same in opposite directions, a second spindle having a spring tending to turn it in a certain direction, a support for the strip supply roll, and a strap connected to said spindles, respectively, and adapted to bear against the periphery of the roll of paper.
2. A strip feeding mechanism comprising a support for rotatably mounting a supply roll, a feeding strap mounted to permanently 120 125 130

frictionally engage the periphery of said supply roll, means to reciprocate said strap intermittently, and means for preventing the rewinding of said strip onto said roll.

5 3. A strip feeding mechanism comprising a support for rotatably mounting a supply roll, a rotatable spindle adjacent to said support, a spring tending to rotate said spindle, a friction strap connected to said spindle, and means for reciprocating said strap in contact with said supply roll.

10 4. A strip feeding mechanism comprising a support for rotatably mounting a supply roll, two rotatably mounted spindles parallel therewith and on opposite sides thereof, a friction strap connected to said spindles, means tending to turn one of said spindles, and means for intermittently rotating the other spindle to reciprocate said strap in contact with the supply roll.

15 5. In a strip feeding mechanism, a support for rotatably mounting a supply roll, a rotatable spindle adjacent to said support, a spring tending to rotate said spindle, a friction strap connected to said spindle, means for reciprocating said strap in contact with said supply roll, and means for preventing the rewinding of the strip onto the supply roll.

20 6. A strip feeding mechanism comprising actuating mechanism, a support for rotatably mounting a supply roll, a rotatable spindle adjacent to said support and having a spring tending to rotate it, a friction strap connected to said spindle, means for reciprocating said strip in contact with said supply roll, a winding drum, and intermediate connecting devices for transmitting motion from said actuating mechanism to said drum, said

devices comprising an automatically yielding member.

25 7. A strip feeding mechanism comprising actuating mechanism, a support for rotatably mounting a supply roll, a rotatable spindle adjacent to said support and having a spring tending to rotate it, a friction strap connected to said spindle, means for reciprocating said strap in contact with said supply roll, a winding drum, and intermediate connecting devices for transmitting motion from said actuating mechanism to said drum, said devices comprising a friction clutch adapted to slip when the strip becomes taut.

30 8. An embossing and printing press comprising actuating mechanism, a wiping pad operatively connected thereto to be actuated thereby, mechanism for feeding wiping paper, and mechanism for winding the waste wiping paper, said feeding and winding mechanism being operatively connected to said actuating mechanism, said feeding mechanism comprising a support for rotatably mounting the supply roll, a rotatable spindle adjacent to said support and having a spring tending to rotate it and a friction band connected to said spindle and adapted to reciprocate in contact with the supply roll, and said winding mechanism comprising a winding drum and a friction clutch between said drum and the actuating mechanism.

35 In testimony whereof I have signed my name to this specification in the presence of two subscribing witnesses, this 27th day of June, 1908.
